(57) **CLAIM**

The ornamental design for a wrist electronic device, as shown and described.

DESCRIPTION

FIG. 1 is a first perspective view of a wrist electronic device, showing the new design;

FIG. 2 is a second perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof;

FIG. 9 is a left-side view of the wrist electronic device in use;

FIG. 10 is a first perspective view of the wrist electronic device in an integrated mode;

FIG. 11 is a second perspective view thereof in an integrated mode;

FIG. 12 is a front view thereof in an integrated mode;

FIG. 13 is a rear view thereof in an integrated mode;

FIG. 14 is a left-side view thereof in an integrated mode;

FIG. 15 is a right-side view thereof in an integrated mode;

FIG. 16 is a top view thereof in an integrated mode;

FIG. 17 is a bottom view thereof in an integrated mode;

FIG. 18 is a left-side view of the wrist electronic device in an integrated mode in use;

FIG. 19 is a first perspective view of the wrist electronic device in an separated mode;

FIG. 20 is a second perspective view thereof in an separated mode;

FIG. 21 is a front view thereof in an separated mode;

FIG. 22 is a rear view thereof in an separated mode;

FIG. 23 is a left-side view thereof in an separated mode;

FIG. 24 is a right-side view thereof in an separated mode;

FIG. 25 is a top view thereof in an separated mode;

FIG. 26 is a bottom view thereof in an separated mode; and,

FIG. 27 is a left-side view of the wrist electronic device in an separated mode in use.

The broken line showing of a human limb in FIGS. 9, 18 and 27 is directed to an environment and for illustrative purpose only. All other broken lines depict portions of the wrist
